UNITED STATES PATENT OFFICE

ARTHUR J. CHANTER, OF BUFFALO, NEW YORK, ASSIGNOR TO THE PIERCE-ARROW
MOTOR CAR COMPANY, OF BUFFALO, NEW YORK, A CORPORATION OF NEW YORK

DESIGN FOR A COMBINED LAMP AND HORN

Application filed July 11, 1932. Serial No. 44,300. Term of patent 14 years.

To all whom it may concern:

Be it known that I, ARTHUR J. CHANTER, a citizen of the United States of America, a resident of Buffalo, in the county of Erie and State of New York, have invented a new, original, and ornamental Design for a Combined Lamp and Horn, of which the following is a specification, reference being made to the accompanying drawing, forming a part thereof.

In the drawing, the figure is a perspective view showing my new design.

I claim:

The ornamental design for a combined lamp and horn substantially as shown.

Signed by me at South Bend, Indiana, this 6th day of July, 1932.

ARTHUR J. CHANTER.
